UNITED STATES PATENT OFFICE.

HARRY EHLIG, OF PEARL RIVER, NEW YORK, ASSIGNOR TO GEORGE R. SWART & COMPANY, INC., OF NEW YORK, N. Y., A CORPORATION OF NEW YORK.

SADDLE-STITCHER ATTACHMENT.

Application filed February 8, 1924. Serial No. 691,333.

To all whom it may concern:

Be it known that I, HARRY EHLIG, a citizen of the United States, and a resident of Pearl River, in the county of Rockland and 5 State of New York, have invented certain new and useful Improvements in Saddle-Stitcher Attachments, of which the following is a specification, reference being made to the accompanying drawings, forming a 10 part thereof.

My invention relates to devices for wire stitching or stapling groups of superposed signatures or sheets in forming pamphlets, magazines, etc. The signatures are usually 15 superposed by the signature gatherer, and are then carried by any suitable conveyor toward the wire-stitching mechanism which presses the signatures tightly together and while so pressed such stitching mechanism 20 inserts the wire staples and clenches same in position.

The objects of my invention are, among other things, to provide a simple and effective attachment for the saddle or support 25 adjacent the wire stitching mechanism whereby the folded signatures may be handled and then held for stitching so as to avoid undesirable frictional engagement with the apex of the saddle and the clencher 30 boxes to prevent off-setting and also injurious marking or otherwise damaging or tearing the surface of the under signatures at or adjacent the longitudinal folds.

Another object of my invention resides 35 in providing means to more accurately align or register the apex of the folded signatures about to be stitched with the clencher points in the boxes mounted on the signature support or saddle.

My improved attachment also embodies 40 other advantageous features of novelty and improvement in handling and stitching signatures in which the various parts are simplified in form and action, and are made 45 more effective and otherwise better adapted for use, all of which will be hereinafter described and then particularly set forth in the appended claims.

The drawings show my improved attachment in a preferred embodiment; however, 50 the inventive idea is capable of being embodied in a variety of mechanical structures with similar advantages and results.

Of the drawings, Fig. 1 is a fragmentary and diagrammatic front view of a stitching

or stapling machine equipped with my improved attachment;

Fig. 2 is an enlarged cross-sectional view taken on the line 2—2 of Fig. 1 looking in the direction of the arrows; and 60

Fig. 3 is a detailed elevation with the front of the saddle support removed taken on the line 3—3 of Fig. 2 looking in the direction of the arrows.

Similar numerals refer to similar parts 65 throughout the several figures.

Referring to Fig. 1, the frame 4 carries the stitcher or stapling heads 5 of any well-known construction to cooperate with a like number of clencher boxes 6 adjustably 70 mounted on the inverted V-shaped saddle or support 7 along which the groups of signatures are carried by any suitable conveyor mechanism not shown. Each clencher box 6 is adjustably secured in position on the saddle 7 by set-screws 8 passing through the elongated slot 9 formed in the saddle 7 and the screws 8 are manipulated through the opening 10 as shown in Fig. 3. The usual reciprocating presser-bars 11 to bend the 80 ends of the wire staples to force the latter over the superposed signatures are slidably mounted in the clencher boxes 6 as shown in Figs. 1 and 2.

Adjacent each clencher box 6 means are 85 mounted on the saddle 7 to project slightly above the apex of the saddle and in alignment with the clencher points in the clencher boxes 6: A preferred embodiment for each stitcher shown in Fig. 1 comprises 90 the bracket 12 having the slot 13 formed therein with the roller 14 pivotally mounted on the pin 15 fastened to the upper end of the bracket so as to be freely rotatable on such pin. Such roller 14 is preferably 95 formed of any suitable fibre or hard rubber material and the periphery is suitably narrowed to a thin edge 16 as shown in Fig. 2. Projecting from within the slot 9 and through the slot 13 in the bracket 12 is the 100 screw-bolt 17 upon which is threaded the nut 18 as shown in Figs. 2 and 3. By loosening the nut 18 the bracket 12 with the roller 14 may be swung downwardly to the inoperative position shown by dotted lines 105 in Fig. 3, or the attachment may be horizontally shifted to any desired position along the saddle 7. When the bracket 12 is held in upright position (shown in full lines in Fig. 3) the peripheral edge 16 of 110

the roller 14 projects slightly above the apex of the saddle 7 and the plane of the clencher points in the boxes 6.

The signatures are held in open position 5 along the saddle 7 by such peripheral edge 16 resting in the fold of the signature so that the successive signatures are not only conveyed along the saddle with a minimum of frictional engagement therewith but also are 10 accurately alined and held on the saddle with their folds in register with the clencher points in the boxes 6.

The foregoing construction embodies the underlying principles of my invention, but 15 various changes or modifications may be made in the structural details without departing from the scope of my improvements defined in the following claims.

I claim as my invention:—

- 20 1. In combination, a support or saddle on which signatures are held in open position, mechanism for stitching said signatures so held including means carried by the saddle, and independently rotatable means adjustably carried by the saddle for holding the signatures above said saddle and in register with said means carried by the saddle.
- 25 2. In combination, a support or saddle on which signatures are held in open position, a stitching mechanism for said signatures comprising a clencher box slidably mounted on said saddle, and independently rotatable means slidably mounted adjacent the clencher box for projecting the signatures from said saddle and in register with said clencher box.
- 30 3. In combination, an inverted V-shaped support or saddle on which signatures are

held in open position, a stitching mechanism for said signatures comprising a clencher box slidably mounted on said saddle, means for projecting the signatures from said saddle and clencher box, and a single means for securing said projecting means in any predetermined position relatively to the apex 45 of the saddle and spaced from the clencher box.

4. In a saddle-stitcher attachment, the combination of an inverted V-shaped support or saddle for groups of signatures, and 50 a freely rotatable roller adjustably secured to the saddle in any predetermined position for holding the signatures at any distance in alinement with the apex of the saddle when stitched.

5. In a signature stitching machine having a stitcher head, a signature supporting saddle positioned beneath the stitcher head and adapted to have groups of signatures fed therewith and positioned beneath the 60 stitcher head to be stitched thereby, a clincher mounted in a longitudinal slot in the saddle in register with the stitcher head and adapted to clinch the stitches inserted in the groups of signatures by the stitcher 65 head, a longitudinally slotted supporting member, a wheel member having a substantially sharp peripheral edge, means freely rotatably securing the wheel to one end of the supporting member, and means past 70 through the slot of said supporting member to adjustably secure the wheel member in the slot of the saddle with its peripheral edge in longitudinal alignment with the stitcher head and clincher.

HARRY EHLIG.
